COMBINED LIGHT TABLE AND WORK BENCH OR THE LIKE

Eugene W. Hawkins and Douglas E. Johnson,
Arlington, Tex.

Filed May 3, 1972, Ser. No. 250,108

Term of patent 14 years

Int. Cl. D6—03

U.S. Cl. D6—4

FIG. 5

FIG. 6

FIG. 7

FIG. 1 is a front view of the combined light table and work bench showing our design;

FIG. 2 is a top view of the construction shown in FIG. 1;

FIG. 3 is a left end view of the construction shown in FIG. 1;

FIG. 4 is a right end view of the construction shown in FIG. 1;

FIG. 5 is a back view of the construction shown in FIG. 1;

FIG. 6 is a bottom view of the construction shown in FIG. 1; and

FIG. 7 is an isometric perspective view of the construction shown in FIG. 1.

We claim:

The ornamental design for a combined light table and work bench or the like, as shown.
